UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT

HOOD CATCH

Application filed November 7, 1929. Serial No. 405,420.

The present invention relates to hood catches, and has for an object to provide a catch which when disengaged will be firmly held in a predetermined position away from the hood against both inward movement into the path of the closing and opening movement of the hood, and against outward movement into contact with the fender and sill surfaces.

10 The present improvements are particularly for use in hood catches of the type disclosed in the patent to Kerr and Pray, #1,312,078, dated August 5, 1919, in which a side engaging clamp is connected to the 15 hold down clamp and presses upon the hood in the hooked relation of the clamp. This lever is apt to obstruct the closing of the hood, and for this reason care must be taken to place it out of the path of the hood before 20 closing the latter. It is proposed in the present embodiment to provide cam means actuated by the spring of the hold down clamp for positively moving and firmly retaining both the side engaging clamp and the hold down 25 clamp in a predetermined position out of the path of the hood in the disengaged relation. A further object is to provide a simple and reliable construction, and one which will not add materially to the cost of manufacture 30 over the previously known types.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a side elevation of a hood catch, partly in section, according to the present embodiment of the invention, and showing the same in clamped relation.

Fig. 2 is a side elevation showing the same disengaged.

Fig. 3 is an elevation seen from the hood side, the clamp being in the same relation as shown in Fig. 1.

Fig. 4 is a front elevation of the keeper employed.

50 Similar reference characters indicate cor-

responding parts throughout the several figures of the drawings.

Referring to the drawings, the hood catch, according to the present embodiment of the invention, consists of a cylindrical barrel 10, flanged at its lower end, as at 11, to provide a reduced passage in which the rod 12 is slidably engaged, the end of the rod within the barrel being provided with a washer 13, between which and the flange 11 a spring 14 is coiled about the rod. A cap 15 having a clamping hook 16 and handle 17 integrally formed therewith is screwed upon the upper end of the barrel.

At its lower end the rod is provided with an eye 18, and is pivotally connected between the side portions of the side engaging clamp by means of a riveted pivot pin 19. The side engaging clamp comprises a forward portion 20 having a bumper formation 21 pressed therein, and spaced parallel side portions 22 bent rearwardly therefrom, and which are pivotally mounted upon a bracket 23 by means of a pin 24. The outer ends of the side portions, beyond the rod 12, are rigidly connected and spaced by a transverse shouleder rivet pin 25.

The spacing of the side portions is such that their upper flat edges 26-26 provide a support against which the lower end of the barrel seats in the disengaged position, as shown in Fig. 2, being yieldably held by the action of the spring 14.

The bracket is provided between the side portions with an upstanding finger wedge portion 27, the inner surface of which is so arranged as to abut the forward portion 20 of the lever in the disengaged position, while the outer surface engages the lower end portion of the barrel 10 with a wedging fit under the action of the spring 14, the barrel being disposed at a converging angle with respect to the forward portion 20 in said disengaged position.

The finger is rounded, as at 28, to cooperate with the rounded end of the barrel with a cam action, so as to insure the outward swinging of the bumper lever.

In the disengaged position, the barrel and side engaging clamp are yieldably but firmly

supported in a predetermined position out of the opening and closing path of the hood, and out of engagement with the sill surface.

The hook 16 of the catch is adapted to engage a keeper 29 secured upon the hood, while the bumper portion 21 is pressed inwardly against an abutment portion 30 formed integrally at the lower end of the keeper plate 31.

19 I have illustrated and described a preferred and satisfactory embodiment of the invention, but it will be obvious that changes may be made therein, within the spirit and scope thereof, as defined in the appended claims.

Having thus described my invention, what I claim and desire to secure by Letters Patent is:—

20 1. In a hood catch, a spring pressed hold down clamp, a pivotally mounted side engaging clamp pivotally connected thereto at a point removed from the pivot mounting of said side engaging clamp, and positioning means adapted to be simultaneously contacted by said hold down clamp and said side engaging clamp to retain them in a predetermined position in the disengaged relation of said hold down clamp under the spring pressure of said hold down clamp.

25 2. In a hood catch, a spring pressed hold down clamp, a pivotally mounted side engaging clamp pivotally connected thereto at a point removed from the pivot mounting of said side engaging clamp, and positioning means adapted to be contacted by said side engaging clamp to limit its outward movement in the disengaged relation and to be contacted by said hold down clamp to limit the inward movement of said side engaging 30 clamp in said disengaged relation under the spring pressure of said hold down clamp.

35 3. In a hood catch, a base, a side engaging clamp pivotally mounted on said base, a spring pressed hold down clamp pivotally connected to said side engaging clamp at a point removed from the pivot mounting of said side engaging clamp, and positioning means on said base adapted to be interposed between said side engaging clamp and said hold down clamp in their disengaged relation to retain them in a predetermined position under the spring pressure of said hold down clamp.

40 4. In a hood catch, a base, a side engaging clamp pivotally mounted on said base, a hold down clamp comprising a rod pivotally connected to said side engaging clamp, a barrel slidably mounted on said rod, and a spring interposed between said rod and barrel and adapted to draw the latter downwardly on said rod, and means on said base adapted to be engaged at one side by said side engaging clamp to limit its outward movement in disengaged relation and to be engaged at its other side by said barrel, as it is drawn down-

wardly on said rod, to prevent the inward movement of said side engaging clamp in said disengaged relation.

5. In a hood catch, a base, a side engaging clamp pivotally mounted on said base, a hold down clamp comprising a rod pivotally connected to said side engaging clamp, a barrel slidably mounted on said rod, and a spring interposed between said rod and barrel and adapted to draw the latter downwardly on said rod, said barrel adapted to be engaged with said side engaging clamp in its downwardly drawn disengaged relation whereby relative pivotal movement of said rod with respect to said side engaging clamp is prevented, and means on said base adapted to be engaged at one side by said side engaging clamp to limit its outward movement in disengaged relation, and to be engaged at its other side by said barrel, as it is drawn downwardly on said rod, to prevent the inward movement of said side engaging clamp in said disengaged relation.

Signed at Bridgeport, in the county of Fairfield, State of Connecticut, this 5th day of November, 1929.

RAYMOND G. MOORE.
